DESIGN FOR AN ASH TRAY

William P. Mader, Detroit, Mich., assignor to
Roethel Engineering Corporation, Detroit,
Mich., a corporation of Michigan

Application October 6, 1947, Serial No. 141,762

Term of patent 7 years

(Cl. D85—2)

To all whom it may concern:

Be it known that I, William P. Mader, a citizen of the United States, residing at Detroit, county of Wayne, State of Michigan, have invented a new, original, and ornamental Design for an Ash Tray, of which the following is a specification, reference being had therein to the accompanying drawings, forming a part thereof, in which:

Fig. 1 is a top plan view of an ash tray showing my new design.

Fig. 2 is a side elevational view thereof; and

Fig. 3 is a sectional elevational view through the line 3—3 of Fig. 1 looking in the direction of the arrows.

I claim:

The ornamental design for an ash tray, substantially as shown.

WILLIAM P. MADER.
